(57) **CLAIM**

The ornamental design for earphones with charging case, as shown and described.

DESCRIPTION

FIG. 1 is a perspective view of earphones of earphones with charging case, shown separately for ease of illustration; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a perspective view of a charging case of the earphones with charging case, shown separately for ease of illustration and in an open configuration; FIG. 10 is another perspective view thereof; FIG. 11 is a front elevational view thereof; FIG. 12 is a rear elevational view thereof; FIG. 13 is a left side elevational view thereof; FIG. 14 is a right side elevational view thereof; FIG. 15 is a top plan view thereof; FIG. 16 is a bottom plan view thereof; FIG. 17 is a perspective view of the earphones with charging case, shown in use with the earphones received in the charging case; and, FIG. 18 is an exploded perspective view of the earphones with charging case. The broken lines in the drawings depict portions of the earphones with charging case that form no part of the claimed design.

1 Claim, 18 Drawing Sheets
